DESIGN FOR A CLOSURE CAP

Albert H. Jung, Flushing, N. Y., assignor to Victor Metal Products Corporation, Brooklyn, N. Y., a corporation of New York

Application August 31, 1939, Serial No. 86,987

Term of patent 7 years

To all whom it may concern:

Be it known that I, Albert H. Jung, a citizen of the United States and resident of Flushing, Long Island, in the Borough of Queens, county of Queens, city and State of New York, have invented a new, original, and ornamental Design for a Closure Cap, of which the following is a specification, reference being had to the accompanying drawing, forming part thereof.

Fig. 1 is a top plan view of a closure cap showing my new design.

Fig. 2 is an elevational view of the same.

Fig. 3 is a bottom plan view of the same.

The characteristic features of the design consist of the peculiar faceted character of the sur-

face of the cap, each facet being identical with the remaining facets and having a surface eccentric to the surfaces of the remaining facets and eccentric to the axis of the cap, each facet terminating in an outwardly concave edge projecting outwardly from the adjacent surface of the adjacent facet and having its greatest thickness at the base of the cap, said thickness decreasing gradually to the apex of the cap where the pointed ends of the facets meet.

I claim:

The ornamental design for a closure cap, substantially as shown and described.

ALBERT H. JUNG.
